ELECTRIC BLASTING CAP

William C. Hunt, Wilmington, Del., assignor to
Hercules Powder Company, Wilmington, Del.,
a corporation of Delaware

Application April 10, 1936, Serial No. 73,602

4 Claims. (Cl. 102—10)

This invention relates to a new and improved electric blasting cap, such as is used in firing commercial explosives, and more particularly relates to an arrangement whereby blasting caps may be protected during shipment and storage, 5 with avoidance of accidental discharge.

As is well known, electric blasting caps are equipped with a pair of lead wires, by which they are connected to a firing circuit after they have been placed within an explosive charge to be detonated. Usually, for the purpose of shipment and storage of such electric blasting caps, the lead wires, often of considerable length, are bundled and tied centrally of the wire bundle, with the free ends of the lead wires and the cap at opposite ends of the bundle.

The customary bundling and tying of the lead wires of such caps is ordinarily sufficient to enable packaging and handling of the caps, but, since the cap itself is wholly unprotected, it is liable to accidental firing by any shock to which it may be subjected, for example, by striking another cap in the package, or by striking the wall of a package during shipment, from being dropped during handling, or otherwise. Such caps are usually loaded with mercury fulminate, diazodinitrophenol, or similar, sensitive high explosive, so that the possibility of accidental firing presents a certain amount of hazard.

Heretofore, attempts have been made to avoid this disadvantage of having the cap exposed to shock, e. g. as in United States Letters Patents 1,912,432 and 1,631,756, but such attempts have not wholly accomplished their purpose, or have 35 involved serious difficulties in removing the lead wires from the bundle without tangling the wires. Moreover, such attempts in the past have necessitated the use of separate elements to form the core and the protective sleeve and the insertion 40 of the wire bundle within said sleeve element, all at considerable cost of materials and labor in packing such electric blasting caps.

It is the object of this invention to provide an 45 arrangement consisting of the lead wires only, whereby such caps will be adequately protected from shock, whether during shipment, storage, or handling, and at the same time provide a ready method of dis-assembling the package without 50 tangling the lead wires.

In accordance with this invention there is provided a protector for the blasting cap in the form of a self-supporting coil, without the use of a sleeve or tube to form either core of the coil or protection over the coil, such as has been nec-

essary in the past with helically wound lead wires.

Having now indicated in a general way the nature and purpose of my invention, I shall proceed to a detailed description of preferred embodiments thereof, with reference to the accompanying drawings, in which Figure 1 is a side view of an electric blasting cap package embodying my invention, Figure 2 is a view in elevation of the device of Figure 1, Figure 3 is a modification of the device of Figure 1, Figure 4 an end view of the device embodying my invention where it is desired to use the invention on short lengths of lead wires, and Figure 5 a side view of the device of Figure 4, Figure 6 an end view of a 10 modification of the device of Figures 4 and 5, and Figure 7 a side view of the device shown in Figure 5.

Referring more particularly to Figure 1 of the accompanying drawings, 1 indicates an electric 20 blasting cap, provided with lead wires 2 which are wound, beginning with the lead wires adjacent to the cap, in the form of what is commonly known as a "honeycomb coil" by moving the lead wires, during the coiling operation on a mandrel whose diameter is approximately the 25 length of the blasting cap, from one end of the coil to the other, so that said lead wires cross the wires beneath them at an angle to the underlying wires, and also form a lock for the underlying wires at the ends of the coil, to prevent 30 collapse of the coil, all as is shown in greater detail in Figures 2, 5, and 7. When the coil has been wound as described, a loop, 2², is formed from the the extending ends of the lead wires, and the end of lead wires 2 passed through said 35 loop, the loop placed about the exterior of the honeycomb coil, pulled tight, and the ends of the lead wires 2 bent back to lock the loop in place. The coil is then removed from the mandrel, and will be found to be interlocked from 40 layer to layer and will be self-supporting, being prevented from uncoiling by the exterior loop 2². The blasting cap 1 is then inserted into the open space forming the core of the coil and is 45 retained there by resting with the base of the blasting cap pressed against the interior of the coil by the spring effect of lead wires 2. The un-insulated ends of the lead wires 2 may be suitably short-circuited, by twisting them together or by twisting them, as shown by 2', about a bare 50 piece of heavier wire 3.

It will be noted that to uncoil the lead wires for use in blasting operations, it will be necessary only to pull the blasting cap 1 from the core of the coil, whereupon lead wires 2 uncoil from the 55

interior of the honeycomb coil as the lead wires are pulled forth, and do so without interference from any pasteboard coil core heretofore used, and without curling or kinking, as has been experienced with blasting cap coils heretofore employed.

Referring now specifically to Figure 3 of the accompanying drawings, which represents a modification of my invention shown in Figure 1, 10 it will be noted that the honeycomb coil of the lead wires is formed by winding on a mandrel whose diameter is approximately the length of the blasting cap, the lead wires 2 starting from the uninsulated extremities of said lead wires 2', forming a loop 2² of the lead wires 2 after the coil is wound, putting the blasting cap 1 and lead wires through said loop and bending back cap and lead wires to form a lock, then placing the blasting cap within the core of the honeycomb 20 coil with the bottom of the blasting cap resting against the interior of the core of the coil and retained in position by the spring of lead wires 2.

It will be noted that, in the form of my invention shown in Figure 3, the bare ends (2') of the lead wires are protected from contact with sources of electricity by being within the core of the honeycomb coil, and consequently do not ordinarily require short-circuiting for protection from stray currents, while at the same time the blasting cap is also protected from striking objects by being within the hollow core of the coil. It will also be noted that this form of my invention also enables the lead wires to be uncoiled from the center of the honeycomb coil by merely 35 pulling out the end 2' of the lead wires, and this without the undesirable curling and kinking heretofore experienced with other forms of cap packages.

Referring now specifically to Figures 4 and 5 of the accompanying drawings, which illustrate a preferred embodiment of my invention with the use of comparatively short lengths of lead wire, 1 represents the blasting cap, 2 the lead wires of said blasting cap, 2' the uninsulated ends of said lead wires, and 4 a band or strap, e. g., of tape or rubber band, to tie down the last convolution of the honeycomb coil. In this embodiment of my invention, the lead wires 2 are coiled in the criss-cross, honeycomb manner hereinbefore described, upon a mandrel whose diameter is slightly greater than the diameter of the blasting cap, 50 commencing with the portions of the lead wires nearest the cap, and, when the coil has been formed, the coil is removed from the mandrel, the blasting cap inserted in the core of the coil, where it is retained by the spring effect of lead 55 wires 2, and by the retaining band or strap 4 placed about the exterior of the coil.

Referring now specifically to Figures 6 and 7 of the accompanying drawings, which represent a modification of my invention shown in Figures 4 and 5, it will be noted that the winding of the

honeycomb coil is commenced with the uninsulated ends of the lead wires, and, after the winding of the coil is completed, the cap and its lead wires are then inserted into the hollow case of the coil and retained there by the spring effect of the lead wires. The band or strap 4 is used on the exterior of the coil, as hereinbefore described.

It will be noted that in the form of my invention shown in Figures 4 to 7 inclusive, the uncoiling of the lead wires before use in blasting operations will be from the interior of the honeycomb coil, without the usual disadvantages of curling and kinking heretofore experienced.

In the winding of the lead wires to form the 15 honeycomb coil of my invention I prefer to use coil winders ordinarily used to form such coils, although I may use any suitable apparatus therefor.

It will be noted particularly, that I do not 20 require any supports or end pieces for my honeycomb coil, nor, as has been stated, any tube within the coil. Thus, except for the binding strip of Figures 5 and 7, I form my blasting cap package solely of the lead wires per se, without resort 25 to the use of any additional materials.

It will be noted that my blasting cap assembly 30 lends itself with advantage to the packing of several such coils in one box, without the complication of entangling lead wires of one blasting cap with another, and without the large packing box or case heretofore required.

What I claim and desire to protect by Letters Patent is:

1. A prepared package comprising a blasting 35 cap having a pair of lead wires wound in the form of a substantially rigid self-supporting, honeycomb coil, the blasting cap being within said honeycomb coil.

2. A prepared package comprising a blasting 40 cap having a pair of lead wires wound in the form of a substantially rigid self-supporting, honeycomb coil, the blasting cap being within said honeycomb coil, and a wire tie composed of the end portion of the lead wires about the exterior of said coil and adapted to prevent uncoiling of said coil.

3. A prepared package comprising a blasting 45 cap having a pair of lead wires wound in the form of a substantially rigid self-supporting, honeycomb coil, said coil having a core 50 diameter approximately the length of said blasting cap, and a blasting cap in said core of said honeycomb coil.

4. A prepared package comprising a blasting 55 cap having a pair of lead wires wound in the form of a substantially rigid self-supporting, honeycomb coil, said coil having a core diameter approximately the diameter of said blasting cap, and a blasting cap in said core of said honeycomb 60 coil.

WILLIAM C. HUNT.
